UNITED STATES PATENT OFFICE.

SAMUEL A. PAYNE, OF SCOTTSBURG, INDIANA, ASSIGNOR OF TWO-THIRDS
TO JAMES L. FISHER AND JOHN M. STOUT, OF SAME PLACE.

HAND-PLANTER.

SPECIFICATION forming part of Letters Patent No. 381,083, dated April 10, 1888.

Application filed January 10, 1888. Serial No. 260,287. (No model.)

To all whom it may concern:

Be it known that I, SAMUEL A. PAYNE, a citizen of the United States, residing at Scottsburg, in the county of Scott and State of Indiana, have invented a new and useful Improvement 5 in Hand-Planters, of which the following is a specification.

My invention relates to an improvement in combined hand corn-planters and fertilizer-distributors; and it consists in the peculiar 10 construction and combination of devices, that will be more fully set forth hereinafter, and particularly pointed out in the claims.

The object of my invention is to provide a 15 hand corn-planter and fertilizer-distributor which shall be extremely cheap and simple, easily operated, and readily packed in a small space when not in use; and these objects I attain by the construction hereinafter described, 20 and illustrated in the accompanying drawings, in which—

Figure 1 is a perspective view of a combined hand corn-planter and fertilizer-distributor embodying my improvements. Fig. 2 is a 25 vertical sectional view of the same. Fig. 3 is a view of the top portion of the planter, showing the frame to which the hopper is fastened and illustrating in dotted lines how the hopper may be collapsed.

A represents a vertical standard of suitable 30 length, width, and thickness, to one side of which, near its lower end, is secured a box, B, which is arranged at a suitable angle, as shown. This box is divided into two compartments, 35 C D, of unequal size, by a partition-plate, E, which has its side that is in the compartment D beveled or inclined, as shown. In the under side of this partition is an inclined channel, F, across the upper end of which is arranged a brush, G. The channel F at its inner 40 end communicates with a seed cup or recess, G', in the bottom of the compartment C.

H represents a slide which is arranged in a 45 longitudinal groove on the lower side of the box B, and is supported by a plate, I, which is screwed to the bottom of said box. The slide H has a circular opening, K, at a suitable distance from one end and a rectangular opening, L, arranged near the said opening K. 50 At the outer end of the said opening L, on the upper side thereof, is a flange or ridge, M.

In the bottom of the plate I, near the center of the same, is a rectangular opening, N, with which the openings K L are adapted to alternately register when the slide is operated. 55 The said bottom plate, I, is also provided near its lower end with a series of openings, O, which are adapted to permit the escape of any particles of the fertilizer which may find their way between the slide and the bottom plate. 60

P represents a hopper, which is made of cotton fabric or other suitable material, has its larger upper end stretched over a frame, R, which is made of wire, and is hinged to the standard by means of staples S, and the lower 65 end of the said hopper is secured to the box B, as shown. This hopper is divided into two compartments by a strip, T, of suitable fabric, which strip has its upper end secured to a cross-bar, U, in the center of the frame R, and has its lower end secured to the partition-plate E.

V represents a hook, which has its upper 70 end hinged to the standard A, and is adapted to engage the frame R when the same is turned to nearly a horizontal position so as to distend the hopper.

W represents a pair of ears, which are secured to one side of the box B on the outer side of the hopper, and between the said ears 75 is fulcrumed a bell-crank lever, X, the lower end of which engages an opening in the upper end of the slide.

Y represents an operating-rod, which has its lower end pivotally connected to the upper 80 arm of the bell-crank lever. The said operating-rod is arranged at a slight angle on one side of the standard A, near the upper end thereof, and is guided in a keeper, Z, attached to said standard. To the upper end of the 85 said rod Y is secured a handle, A'.

The operation of my invention is as follows: 90 The corn is placed in that compartment of the hopper which communicates with the compartment C of the box, and the fertilizer is placed in that compartment of the hopper which communicates with the compartment D of the box. A portion of the corn finds its way into the recessor cup G', and the fertilizer is supported on the upper side of the slide. 95 The field to be planted is laid off in furrows or cross-checked, as may be preferred, and the 100

operator grasps the machine by the handle and lowers the machine at regular intervals into the furrow which he is following. While the machine is suspended from the handle and is not in contact with the earth its gravity causes the rod Y to draw the bell-crank lever upward, so as to move the slide rearward and cause the same to cut off the channel F and the bottom of the fertilizer compartment of the hopper. When the lower end of the standard comes in contact with the bottom of the furrow, the operator forces the handle-rod downward, which causes the slide to move forward, so that its opening K registers with the channel F, and the grains of corn in the said channel are dropped through the said opening into the furrow. As the operator draws his hand upward to raise the machine from the ground, the rod Y moves upward and causes the bell-crank lever to move the slide rearward and the flange on the said slide at the lower end of the opening L sweeps a suitable quantity of the fertilizer over the bottom plate, I, and when the said opening L registers with the opening N the fertilizer is dropped into the furrow in the same hill with the corn.

The machine may be readily carried and operated with one hand. When the machine is not in use, the hook-rod is disengaged from the frame R, and the latter is swung downward against the standard, as illustrated in dotted lines in Fig. 3, thereby collapsing the hopper and enabling the machine to be stored in a very small space.

Having thus described my invention, I claim—

1. In a planter, the combination of the box having the compartments C D and the bottom opening, N, and the slide arranged on the bottom of the box, under the lower edge of the partition, between the compartments, said slide having the openings K L, the latter being provided with the upwardly-projecting flange at its lower ends, substantially as described.
2. The combination, in a hand corn-planter, of the standard, the box secured thereto near its lower end, the slide arranged in the said box, the flexible hopper having its lower end secured to the box, the frame distending the upper end of the hopper and having one side

hinged to the standard, the hook to engage the free end of the said frame and thereby distend the hopper, the operating-rod guided in the keeper on the standard, and a bell-crank lever connecting the lower end of the said rod to the slide, substantially as described. 55

3. In a combined hand corn-planter and fertilizer - distributor, the combination of the standard A, the box B, secured thereto and communicating with the lower end of the hopper, said box having the compartments C D, the slide arranged under the said box and having the openings K and L, the latter provided with the upwardly - projecting flange at its lower end, the plate I, secured under the bottom of the box and supporting the slide and provided with the opening N, for the purpose set forth, the operating-rod guided in a keeper on the standard and adapted to be reciprocated, and connections between the said rod and the slide to operate the latter, substantially as described. 60 65

4. In a hand corn - planter, the hopper P, made of cotton fabric or other suitable flexible material, the frame R, to which the upper end of the hopper is secured, said frame being hinged to the standard of the corn-planter, and the rod V, to engage the hopper and hold it extended, as set forth. 70

5. In a hand corn-planter, the hopper having its lower end rigidly secured to the standard or leg of the planter and its upper end hinged to said standard, whereby the hopper may be collapsed, and the locking device to hold the hopper distended, as set forth. 80 85

6. In a hand corn-planter, the combination of the standard A, the box B, secured thereto and having the partition E, forming compartments C D, one side of said partition being inclined or beveled, the brush G, secured to the outer side of the partition, the slide, and the hopper secured to the box and having the partition T, as set forth. 90

In testimony that I claim the foregoing as my own I have hereto affixed my signature in presence of two witnesses. 95

SAMUEL A. PAYNE.
